UNITED STATES PATENT OFFICE

2,439,252

PENCIL SHARPENER

Clayton E. Jordan, Prescott, Ariz.

Application April 18, 1945, Serial No. 588,907

2 Claims. (Cl. 120—85)

1

The present invention relates to new and useful improvements in pencil sharpeners and more particularly to a device of this character embodying a pair of telescoping parts adapted for movement one within the other and in which one of the parts carries a rotating sharpening element actuated through the movement of the parts relative to each other.

A further object of the invention is to provide a pencil sharpener of this character and in which the telescoping parts are adapted for operation by one hand of a person for operating a rotating sharpening element and in which a pencil is held in engagement with said sharpening element by one of said telescoping parts.

A further object of the invention is to provide an apparatus of this character of simple and practical construction, which is neat and attractive in appearance, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a view in top plan of the device.

Figure 2 is a side elevational view.

Figure 3 is an elevational view showing one edge of the device.

Figure 4 is a view in bottom plan of the device.

Figure 5 is a vertical sectional view taken on the line 5—5 of Figure 1 and drawn to a larger scale.

Figure 6 is a fragmentary sectional view taken substantially on a line 6—6 of Figure 5, and

Figure 7 is a view in elevation of the cutter.

Referring now to the drawings in detail wherein, for the purpose of illustration, I have disclosed a preferred embodiment of the invention, the numeral 5 designates a casing of substantially rectangular shape in cross section, and over the top end of which is telescopically fitted a cover 6 for the reciprocating movement of the casing into and out of the cover.

The bottom end of the casing 5 is formed with an opening 7, the walls of which are formed with an annular groove 8 rotatably receiving the flange 9 of a conical sharpening device 10 having its wide end open in registry with the opening 7.

Longitudinally extending openings 11 are formed in the cutter 10 and the interior of the cutter is formed with spiral teeth 12.

2

The smaller end of the cutter 10 is formed with a longitudinally extending stem 13 journaled in an opening 14 in the end of the casing 5 opposite from the opening 7.

5 A gear 15 is secured to the cutter adjacent its smaller end operatively engaged with a gear 16 secured on a sleeve 17, the sleeve having a flange 18 adjacent one end thereof rotatably mounted in a groove 19 formed in the outer end of the casing 5. A shaft 20 is positioned in the sleeve 17 and is formed with helical grooves 21 engaging similar ribs 22 formed on the inside of the sleeve whereby to convert the reciprocatory movement of the shaft into rotary movement of the sleeve to thus rotate the cutter 10 through the gears 15 and 16.

One end of the shaft 20 extends through an opening 23 in the inner end of the casing 5 for suitably attaching the shaft to the cover 6.

20 The top end of the cover 6 is formed with a tubular guide 24 split longitudinally, as indicated at 25, to form a plurality of resilient fingers 26 for gripping a pencil inserted therein to thus secure the pencil against rotation.

25 The bottom end of the casing 5 is provided with a loop 27 adapted to receive the thumb of a person, while the cover 6 is provided with a pair of finger-engaging loops 28 to thus hold the casing 5 in one hand, and upon a movement of the casing 5 and cover 6 inwardly and outwardly of each other in a telescoping movement, the helical ribs and grooves of the sleeve 17 and shaft 20, during reciprocation of the shaft in the sleeve, will cause a rotation of the sleeve in opposite directions and thus drive the cutter 10 in opposite directions.

30 During movement of the casing 5 and cover 6 inwardly of each other, a pencil, not shown, inserted in the fingers 26 will be moved into the cutter 10 into engagement with the spiral teeth 12 and said cutter 10 will be rotated in a direction to sharpen the pencil which will be withdrawn relative to said cutter when said casing 5 and cover 6 are moved outwardly of each other.

40 45 Shavings and waste during the cutting action are discharged from the cutter through the openings 11.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

50 55 It is to be understood, however, that even

though I have herein shown and described a preferred embodiment of my invention that the same is susceptible to certain changes fully comprehended by the spirit of the invention as herein described and the scope of the appended claims.

Having thus described the invention, what I claim is:

1. A pencil sharpener comprising a pair of telescopically engaged relatively movable members, one of said members embodying means for holding a pencil therein, a cutter rotatably mounted in the other member, and means connected to the cutter and operable by a movement of said members relative to each other to actuate the cutter, the first mentioned member during movement thereof feeding the pencil into the cutter and withdrawing the same therefrom alternately.

2. A pencil sharpener comprising a pair of telescopically engaged members, one of said members embodying pencil holding means, a hollow conical cutter with internal spiral teeth rotatably mounted in the other member, a sleeve rotatably

mounted in said second-named member operatively engaged with the cutter, and a shaft slidably mounted in the sleeve and interengaged therewith to convert the reciprocatory motion of the shaft to rotary motion of the sleeve upon a movement of said members toward and away from each other, the first mentioned member during movement thereof feeding the pencil into the cutter and withdrawing the same therefrom alternately.
